(57) **CLAIM**

An ornamental design for a keel-weighted fishing lure head, as shown and described.

DESCRIPTION

FIG. 1 is a front and side perspective view of a keel-weighted fishing lure head showing the new design; FIG. 2 is a rear and opposite side perspective view thereof, showing the inside cavity wherein the head of a baitfish is inserted;

FIG. 3 is a right side elevation view thereof;

FIG. 4 is a left side elevation view thereof;

FIG. 5 is a top plan view thereof;

FIG. 6 is a bottom plan view thereof;

FIG. 7 is a rear elevation view thereof; and,

FIG. 8 is a front elevation view thereof.

The solid line showing illustrates the claimed features within the design for the claimed article of manufacture.

The shading is provided to illustrate contour and material type only and is not an indication of texture, gloss, etc.
